UNITED STATES PATENT OFFICE.

WALTER A. HEINRICH, OF ST. LOUIS, MISSOURI, ASSIGNEE, BY MESNE ASSIGNMENTS,
TO W. N. MATTHEWS CORPORATION, OF ST. LOUIS, MISSOURI, A CORPORATION OF
MISSOURI.

SYSTEM OF PAINTING.

Application filed August 29, 1921. Serial No. 496,570.

This invention relates to a new and useful improvement in a system of painting designed especially for use in painting oil tanks, ships, and the like, the object being to 5 suspend a paint tank or container provided with a spray head from an adjustable boom, whereby compressed air supplied to the spray head through the flexible tube leading from a source of compressed air may be utilized 10 in spraying paint on the surface or wall to be painted, means being provided whereby the operator may adjust the tank and its carried spray head vertically to paint the surface in vertical strips.

15 In a companion application, Serial No. 469,427, filed by me May 14, 1921, now patent No. 1,440,147 I have shown a construction designed for the same purpose as the one herein illustrated, but in which the guide ropes 20 which serve to hold the tank and spray head the proper distance from the surface to be painted were free to move. In my present invention, these guide ropes have their weighted ends connected together and are 25 spaced the proper distance by a skeleton frame from the surface to be painted. Also, my present invention contemplates a peculiar form of guyed anchor for the inner end of the boom whose guy ropes, preferably not 30 less than three in number, are designed to be anchored to the ground or secured to the edges of the tank, as the case may be.

The boom in the present construction is also of novel form and contains a manipulative winding drum or air motor by which 35 the paint tank can be raised or lowered relative to the space to be covered. The weighted ends of the guide ropes for the paint tank are connected together by a skeleton 40 frame which also serves to space said weighted ends the proper distance from the surface being covered. The guy ropes and guide ropes are preferably in the form of light 45 twisted wire cables and are mounted on sheaves whereby they may be wound when desired so as to occupy but little space for transportation purposes and at the same time be in readiness for immediate use. By making the parts light and portable they can 50 be installed in position by one man, but usually three men constitute a crew.

In the drawings,

Figure 1 is a top plan view of an oil tank

equipped with an apparatus for carrying out my system of painting. 55

Figure 2 is a top plan view of the paint tank.

Figure 2^a is a detail view of one of the guiding arms for the paint tank.

Figure 3 is a front elevational view of a 60 paint tank and its guiding and supporting means.

Figure 4 is a top plan view of the boom anchor.

Figure 5 is a side elevational view of one 65 of the casting sheave hubs.

Figure 6 is an edge elevational view of one of the sheaves.

Figure 7 is a vertical sectional view 70 through one of the sheaves.

Figure 8 is a side elevational view of the boom anchor.

Figure 9 is a top plan view of the boom and its carried parts.

Figure 10 is a side elevational view of the 75 front end of the boom.

Figure 11 is a front elevational view showing the boom truck and winding drum.

Figure 12 is a top plan view of the weight and guide rope spacing frame. 80

Figure 13 is a side elevational view of said frame.

Figure 14 is a detail view of the ground anchor.

Figure 15 is a side elevational view of a 85 form of hook employed in lieu of the ground anchor.

Figure 16 is a plan view of another form of hook.

Figure 17 is a detail view of the form of 90 hook shown in Figure 16.

In the drawings, referring to Figure 1, A indicates a boom anchoring tripod which is preferably arranged in position at the center of a tank. As shown in Figures 4 95 and 8, this anchor consists of arms 1 arranged parallel to each other and bent to form supporting legs for a platform plate 2. This platform plate provides a mount for a swivelling rod 3, preferably having an eye 4 at its end, by which a rope or cable may be attached thereto for the purpose of securing one end of the boom in position. Each leg of this anchoring tripod provides 100 a mount for a sheave, preferably consisting 105 of the side plates 5 and hub casting 6.

The hub casting 6 is provided with a series of perforations registering with perforations in plates 5 for receiving a pin 7 adapted to pass through corresponding openings in the legs 1, whereby each sheave may be locked in position. Each sheave has a fine wire cable or rope 9 mounted thereon and this cable carries a snap hook 10 at its outer end (see Figure 14). This snap hook is designed to be engaged with the swivel eye 13 of a grab hook 14 (as shown in Figure 15) or 15 (as shown in Figures 16 and 17) and thus the wire cable 9 becomes a guy rope for the anchoring tripod.

Where the tank to be painted is not provided with an overhanging eave, as is sometimes the case, after positioning the boom anchor at approximately the center of the tank, the cables 9 are dropped over the side edges, and after securing the ground anchors into the ground, snap hooks 10 are engaged with the swivel eyes of the ground anchors 15. After this is done, the sheaves are rotated so as to take up any slack in the cables or guy ropes 9 and draw them taut, the pin 7 being inserted to hold the sheaves in locked position.

16 indicates the inner section of a boom having an eye 17 secured in its end (see Figure 9) by which the inner end of the boom may be connected by a rope 18 to the eye 4 of the swivelling anchor rod. Boom 16 is connected by a reducing coupling 19 to another boom section 20 in turn connected by a reducing coupling 21 to an outer and smaller boom section 22. All of these boom sections are preferably in the form of hollow pipes and for purposes of transportation may be nested or telescoped together so as to occupy the least possible space.

On one of these boom sections is detachably secured a truck frame consisting of bars 23 and 24, said bars being connected to a channel member 25 under the ends of which are rollers 26. In this manner the outer end of the boom can be moved around the tank, the rollers 26 being supported by the roof of the tank.

27 indicates what may be designated as an agricultural seat, detachably secured to one of the boom sections and behind a frame composed of bent members 28 and 29 on which are mounted a winding drum 30 and an operating shaft 31, the latter being provided with crank handles 32 by which an operator seated in seat 27 may manipulate the winding drum to pay out or take up a rope or cable 33 passing over a sheave 24, mounted in the outer end of the boom and which rope or cable 33 supports a paint tank 35.

The winding drum and shaft 31 are geared together, as shown in Figure 9, and the operator by manipulating this drum may slowly raise or lower the paint tank. This

system might be replaced by an air motor. The outer end of the boom has a cross-arm 36 mounted thereon (see Figures 3 and 9), which cross-arm may be braced by a bar 37. The ends of this cross-arm are provided with brackets 38 provided with mounts for sheaves 39 which may be similar to the sheaves comprising the parts 5 and 6 hereinafter referred to.

40 indicates a sheave guard arranged over the sheaves 39. Each sheave 39 carries a wire rope or cable 41 constituting guide ropes for the paint tank and each guide rope is provided with a weight 42 at its lower end, which weight may resemble the well known sash weight. Each weight 42 is provided with an opening to receive a spacing bar 43 which is held in position by set screws 44. The weights 42 may thus be adjusted toward or from each other.

45 indicates rods or pipes mounted in the weights by means of set screws 46 and whose inner ends are preferably bifurcated and spread apart as at 47 to engage the wall of the tank and by biting thereinto prevent undue swaying of the guide ropes. The inner ends of these rods 45 are spaced apart by a pipe or rod 48 screwed into the T-couplings 49 in the length of the rods 45.

The paint tank 35, before referred to, is preferably made of galvanized sheet iron having a band 50 at its top provided with lugs or ears 51 in which are pivotally mounted bolts 52 having butterfly nuts 53 on their upper ends. These bolts are designed to be received in recesses in the edges of a casting 54, which casting carries a spray head 55, a pressure gauge 56, and a reducing valve 57, all of which may be connected and are utilized for the purposes described in the companion application.

By making the paint tank separable from the head casting carrying the above mentioned parts, it is possible to remove the paint tank from the apparatus and replenish it with a new supply of paint.

This head casting is provided with guiding arms 58 (Figures 2 and 3) having openings 59 in their ends into which guide ropes 41 may be introduced from the side through the obliquely disposed slots 60.

In operation, if the guy ropes 9 are to be secured to the ground anchors, such are employed. Or, if the grab hooks shown in Figures 15 and 16 are to be used, they are placed in position and the guy ropes drawn taut. The boom is now anchored to the swivel rod and the drum truck arranged in position. The weighted guide ropes 41 are paid out from the sheaves 39 on the cross arm of the boom, preferably with the lower ends of the weights 42 just clearing the ground. One man occupies seat 27 and by signal raises or lowers the paint tank according to the directions of the painter who

stands on the ground and regulates the supply of air to the apparatus. The third assistant may be employed to have a full can of paint in readiness to be attached to the head casting 54 when needed and also to assist in adjusting the skeleton frame which connects the weights 42. The operator who manipulates the drum may use the cross bar 25 on the drum truck as a foot rest. The connection between the inner end of the boom and the tripod anchor is preferably made by means of a rope or cable which not only constitutes a flexible connection but one which can be let out or taken up to properly mount the boom on tanks of different diameters, and, of course within a certain range of diameters.

In view of the above, it will be seen that the several objects of the invention are achieved and other advantageous results attained.

As many changes could be made in carrying out the above constructions without departing from the scope of the invention, it is intended that all matter contained in the above description or shown in the accompanying drawings shall be interpreted as illustrative and not in a limiting sense.

What I claim is:

1. A painting system comprising boom-anchoring means adapted to be positioned within the projected peripheral outline of a tank, a boom swiveled on said means, a truck frame associated with said boom adapted to rest and move about the roof of said tank, a paint tank suspended from the truck, winding means on the boom adapted to control the elevation of said tank, guide ropes for said paint tank suspended from said truck and means for holding the ropes in a predetermined spaced relationship to said tank.

2. A painting system comprising boom-anchoring means adapted to be positioned substantially centrally above a tank, a boom rotatably fastened to said anchoring means, a truck frame associated with the boom adapted to rest upon the roof of said tank and move about its periphery, said truck frame projecting over the edge of the tank, a paint tank suspended from the overhanging truck and winding means for controlling the elevation of said tank.

3. A painting system comprising boom-

anchoring means adapted to be positioned substantially centrally above a tank, a boom rotatably fastened to said anchoring means, a truck frame associated with the boom adapted to rest upon the roof of said tank and move about its periphery, said truck frame projecting over the edge of the tank, a paint tank suspended from the overhanging truck, winding means for controlling the elevation of said tank, guide ropes suspended from said truck for guiding the paint tank, means for weighting said ropes and means for holding them in substantially predetermined positions, whereby the movements of the tank may be controlled.

4. A painting system for structures comprising a sectional boom, weighted guide ropes suspended therefrom, a paint tank and spray head guides by said ropes, means for manipulating said tank and spray head and means associated with weighted ropes for engaging the said structures, whereby predetermined positions of the guide ropes may be substantially maintained.

5. A painting system for structures comprising a sectional boom, weighted guide ropes suspended therefrom, a paint tank and spray head guided by said ropes, means for manipulating said tank and spray head, means associated with weighted ropes for engaging the said structures, whereby predetermined positions of the guide ropes may be substantially maintained and means mounted between said weighted ropes for maintaining a predetermined distance between them.

6. A painting system comprising in combination weighted guide ropes, painting means movable vertically with relation to said ropes and adapted to be guided thereby, and means for spacing said weighted guide ropes with relation to each other and to the surface to be painted.

7. A painting system for surfaces comprising in combination weighted guide ropes, means for holding said weighted guide ropes in spaced relation to one another and to said surfaces being painted, spraying means guided by said ropes and means for moving said spraying means vertically.

In testimony whereof I hereunto affix my signature this 26th day of August, 1921.

WALTER A. HEINRICH.
